UNITED STATES PATENT OFFICE.

GUSTAVE C. HAYSLER, OF CLINTON, MISSOURI.

WASHBOARD.

No. 867,722.

Specification of Letters Patent.

Patented Oct. 8, 1907.

Application filed March 27, 1907. Serial No. 364,773.

To all whom it may concern:

Be it known that I, GUSTAVE C. HAYSLER, a citizen of the United States, and a resident of Clinton, in the county of Henry and State of Missouri, have invented 5 an Improved Washboard, of which the following is a specification.

My invention is an improvement in wash boards, and consists in certain novel constructions and combinations of parts as will be hereinafter described and 10 claimed.

In the drawing, Figure 1 is a perspective view partly broken in section of the wash board embodying my invention. Fig. 2 is a vertical longitudinal section thereof on about line 2—2 of Fig. 1. Fig. 3 is a cross section 15 of the board. Fig. 4 is a detail enlarged section showing the construction of one of the side posts whereby it secures the edge of the rubber and the leg. Fig. 5 is a detail perspective view of one of the legs; and Fig. 6 is a detail perspective view showing the inwardly deflected wing of the side post engaged in the kerf of the 20 leg.

In carrying out my invention, I construct the wash board with a body portion A, a rubber B, and legs C, each of special construction as more fully described 25 hereinafter. The body portion A is to be pressed out of suitable sheet metal of any proper and desired gage, and is formed with the top plate A', the back plate A², and the brace portion A³ pressed forwardly from the back plate, forming at its upper end a soap-holding 30 shelf a³, and at its lower end a shoulder a⁴, and the said brace portion is arched from side to side as best shown in Fig. 3, so it will firmly support the corrugated rubber B when the latter is applied thereto. The body portion A also has at its opposite side edges the posts D 35 bent from the side edges of the main plate forwardly and inwardly as shown in Figs. 3 and 4, and having their free edges deflected forwardly and inwardly into the tubular posts forming upright wings d which enter the kerfs or longitudinal grooves C' in the legs C when 40 the latter are inserted in the side posts as shown in Figs. 1, 2, 3, 4 and 6 of the drawing. This construction not only operates to more securely hold the legs C, but the latter by pressing the wings rearwardly, cause the side posts D at their bent portions d' to bear tightly against 45 the side edges of the rubber B to hold the same firmly in place when the rubber is applied as shown in Figs. 1, 2, 3 and 4 of the drawing.

The rubber B is corrugated as shown, and is bent on a middle line so its side portions incline at an angle, and 50 the said rubber projects at its side edges beneath the free edges of the side posts in order to be held thereby as before described, and at its upper and lower ends the rubber B is wired at B' and B² forming on its rear side the shoulders which engage above and below the 55 forwardly pressed reinforcing portion of the body, in

order to secure the rubber in connection with said reinforcing portion, as will be understood from Fig. 2 of the drawing. It will also be noticed from Fig. 2 that the upper bead of the rubber forms a front wall for the soap shelf a³, and thus aids in securing the soap on the shelf 60 in the use of the invention.

By varying the length of the kerfs C' in the legs C, the latter may be adjusted as will be understood from dotted lines Fig. 1 to project any desired distance below the side posts of the body portion, and the said legs 65 may be removed and replaced to suit the convenience of the user.

I claim:

1. A wash board comprising a body having a main plate, and provided with a forwardly projecting pressed 70 rubber reinforcing portion, having the soap shelf at its upper end, and a shoulder at its lower end, the sides of the main plate being bent forwardly and returned forming side posts, the free edges of which are deflected forwardly within the posts, a rubber having upper and 75 lower beads engaging above and below the forwardly pressed portion of the main plate, and projecting at its side edges under the free edges of the side posts for engagement thereby, and legs having longitudinal kerfs or 80 grooves and projecting into the lower end of the side posts with the kerfs or grooves receiving the inwardly projecting wings of said posts, substantially as and for the purposes set forth.

2. A wash board, comprising a main plate, having its 85 side edges bent forming the tubular upright side posts and having the wings projecting into the said posts, and the legs fitting within the posts and having longitudinal kerfs or grooves receiving the wings thereof, substantially as set forth.

3. A wash board, comprising a main plate having the 90 forwardly pressed rubber reinforcing portion, and having its side edges curved forwardly and returned forming tubular side posts, a rubber fitting over the reinforcing portion of the main plate, and projecting at its side edges beneath the free edges of the tubular side posts, and the 95 legs fitting within the lower ends of the tubular side posts, substantially as set forth.

4. A wash board comprising a main plate, having the 100 forwardly pressed reinforcing portion, and the tubular side posts, and a rubber fitted over said reinforcing portion and conforming generally thereto and having its side edges projecting into the tubular side posts and engaged and clamped by the free edges thereof, and provided at its upper and lower ends on its rear side with beads overlapping the reinforcing portion of the main plate, substantially as set forth.

5. The combination in a wash board, of a main plate having its sides curved forwardly and returned, forming tubular side posts and having the wings projecting into the said posts, a rubber fitted to the main plate, and having its side edges projecting into the tubular side posts, and the legs fitting within the lower ends of the tubular side posts and having longitudinal grooves receiving the inwardly projecting wings thereof, substantially as and for the purposes set forth.

GUSTAVE C. HAYSLER.
